UNITED STATES PATENT OFFICE.

JUSTUS A. TRAUT, OF NEW BRITAIN, CONNECTICUT.

BOTTLE-STOPPER.

SPECIFICATION forming part of Letters Patent No. 400,272, dated March 26, 1889.

Application filed February 13, 1889. Serial No. 299,717. (No model.)

To all whom it may concern:

Be it known that I, JUSTUS A. TRAUT, a citizen of the United States, residing at New Britain, in the county of Hartford and State 5 of Connecticut, have invented certain new and useful Improvements in Bottle-Stoppers, of which the following is a specification.

My invention relates to improvements in bottle-stoppers of the class which have an 10 expansible portion within the neck of the bottle, and the chief object of my invention is simplicity and economy in construction.

In the accompanying drawings, Figure 1 is a plan view of my bottle-stopper. Fig. 2 is 15 a vertical section on line $\alpha\alpha$ of Fig. 1, together with a portion of a bottle, the central member of the stopper being shown in elevation. Fig. 3 is a plan view of the cap-plate of said stopper. Fig. 4 is a front elevation 20 of my bottle-stopper with a slight modification, and Fig. 5 is a side elevation thereof.

6 designates the cap-plate designed to rest upon the mouth of the bottle A and provided with a central oblong orifice, 7, (most clearly 25 shown in Fig. 3,) and with two downwardly-projecting handles, 8 8.

9 designates a plug centrally perforated and provided with a conical lower end, 10.

11 is a cylindrical block of rubber or equivalent 30 expansible material, which is also centrally perforated, and 12 designates a bolt having a flat shoulder under its head at its lower end and a flattened shank, 13, at its upper end, the edges of which are threaded. The 35 body of said bolt passes through the cylindrical block and conical-ended plug, while its flattened shank extends through the oblong opening 7 in the cap-plate 6 and is provided with the thumb-nut 14.

40 In the construction shown in Figs. 1, 2, and 3 I intend to form the cap-plate 6 and nut 14 of sheet metal, and the conical-ended plug 9

of a separate piece of proper material—as, for instance, wood. If desired, however, the cap-plate 6 and nut 14 may be made of cast 45 metal, in which case the conical-ended plug or portion may be formed in one and the same piece with the cap-plate 6, and in skeleton form, as shown by the skeleton plug 15 in Figs. 4 and 5, said plug having the conical 50 lower end, 10, substantially as in the construction first described.

In operation the stopper is inserted within the neck of the bottle, while the operator with one hand prevents the cap-plate from rotating and with the other hand turns the nut 14. The flattened shank of the bolt by being fitted to the oblong hole in the cap-plate 6 is prevented from rotating so long as the cap-plate 55 is held stationary. Turning the nut in a direction to draw the head of the bolt upward expands the cylindrical block 11 within the mouth of the bottle to firmly close the same, as in ordinary stoppers of this class. Turning the nut in the reverse direction will loosen 60 the stopper.

I am aware of the prior patent to myself, as well as patents to others, for internal bottle-stoppers in which an elastic block is expanded within the neck of the bottle under 70 the influence of pressure against a cone face, and I hereby disclaim the same.

I claim as my invention—

The herein-described bottle-stopper, consisting of the cap-plate provided with an oblong opening and handles, a conical-ended plug, an expansible block, the bolt 12, having a flattened shank, and the thumb-nut 14 secured thereon, substantially as described, and for the purpose specified.

JUSTUS A. TRAUT.
